MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA

MANIFOLDING ATTACHMENT FOR TYPEWRITERS.

1,408,345.

Specification of Letters Patent. Patented Feb. 28, 1922.

Application filed February 2, 1920. Serial No. 355,825.

To all whom it may concern:

Be it known that I, MALCOLM L. COSSITT, a citizen of the United States, residing at Alameda, in the county of Alameda and State of California, have invented certain new and useful Improvements in Manifolding Attachments for Typewriters, of which the following is a specification.

My invention relates to manifolding attachments to typewriting machines and other type impression machines.

The object of my invention is to provide a simple, cheap and effective attachment for manifolding, which can be readily applied to various machines with practically no change or alteration in the machine, and by the use of which the ordinary carbon sheets are wholly discarded, while still permitting the duplication to be effected upon loose sheets of paper.

To this end my invention consists in the novel manifolding attachment which I shall hereinafter fully describe, by reference to the accompanying drawings in which, Fig. 1 is a top plan view of a typewriting machine (the cluster of type-bars being omitted) showing the application of my attachment, with the manifolding or impression ribbon down to its functional position, as it would lie between two sheets of paper, if said sheets were in the machine.

Fig. 2 is an end view of a portion of the frame of the machine, showing the application of the end bracket of my attachment.

Fig. 3 is a sectional view on the line 3—3 of Fig. 1, showing the cam-action to effect the distorted path of travel of the manifolding ribbon in descending to its functional position.

Fig. 4 is a section on the line 4—4 of Fig. 1.

Fig. 5 is a sectional view of a portion of the manifolding ribbon, showing its detachable connection with the carrying arms.

1 in Fig. 1 indicates generally such portion of a typewriter as will be sufficient to understand the application thereto of my attachment. 1' are the keys, 2 is the platen, 2' is the spacing ratchet, 3 the ribbon of the machine, 3' are the ribbon drums, and 3'' is the spacing lever, 21 is the paper guide-apron and 22 is the scale bar.

My manifolding attachment comprises essentially two arms 4 connected at one end

by a rod 5, and having extending between 55 and connected with their other ends a manifolding ribbon 6. This structure is fitted to the typewriter in such manner, that the arms and the ribbon they carry may be turned with the connecting rod as an axis, 60 to an elevated position above the platen, as shown by the dotted lines in Fig. 3, and may be turned down again to carry the ribbon to the type-impact receiving face of the platen and in relatively close proximity thereto, as 65 shown in Figs. 1 and 3.

According to the particular construction of any given typewriter, the specific mounting of the attachment will vary to suit the case. In the present illustration I have shown the arm connecting rod 5 as carrying terminal brackets 7, Figs. 1 and 2, in which the rod is journaled, adapting it to turn on its axis. The bases 8 of these brackets are screwed down by the screws 8' to the frame 75 of the platen-carriage and serve as top bearings for the shaft 23 of the platen, Fig. 2. In practice this fitting of the attachment to the machine is readily effected by simply removing the platen-shaft top-bearings belonging to the machine and substituting the brackets 7. By this fitting of the attachment, the rod 5 thus extends across the machine at the back of the platen, and the arms 4 play up and down just beyond the ends 85 of the platen.

The arms 4 are curved on an arc approximately concentric with the platen axis, so that, when down, they conform more or less to the curvature of the platen. The arms 4 90 also are long enough to carry their manifolding ribbon down to the face of the platen, to lie in the line of the type-impact, and relatively close to the platen surface. This arrangement is necessarily provided for by 95 such calculation as may be required by different machines. But in most cases, it will be found that the convenient location of the rod 5 with respect to the platen axis is such that means must be provided to produce an 100 eccentric or distorted path of the manifolding ribbon 6 to draw it in towards the platen when it is being turned down to its functional position, in order that it may clear the usual index pointer of the machine and get 105 in behind said pointer, and then move outward again in its final position to clear the platen surface.

In the present instance this is the case, and I therefore fit the ends of the rod 5 adjustably in the brackets 7, as by the sliding bearing blocks 9, Fig. 2, in said brackets, 5 controlled by springs 10. Upon the rod 5 just inside the brackets are secured cams 11, which impinge on rollers 12 fixed in the brackets. The effect of this mounting is as follows: The rod 5 being above the horizontal plane of the platen axis, it would follow that, in the absence of provision to the contrary, the path of the ribbon 6 in moving down would carry it outside of the index pointer 13 of the machine, Fig. 1. 10 But in the present construction as the arms 4 and ribbon 6 begin to descend the cams 11 acting on the rollers 12 force the rod 5 bodily backward, thus changing its position relatively to the platen, and thereby drawing inwardly toward the platen the path of the descending ribbon. This continues until the apex of the index-pointer 13 is reached at which time the ribbon 6 is well within said pointer, that is on the platen side of it. 15 The ribbon thus passes in behind the pointer and between it and the platen, as in Fig. 1 and thereupon the cut-out portion shown at 11' of the cams, Fig. 3, coating with the rollers 12, allows the springs 10 to 20 force the rod 5 back to its initial position; so that as the ribbon arrives at its lowest point which is its functional position it is removed sufficiently from the platen surface to present no interference to the proper 25 rolling of the paper behind it, as will presently appear in connection with the description of the general operation of the attachment. In this lowest or functional position of the ribbon 6 it is held firmly from further arcuate movement by the points 11" 30 of the cams resting on the rollers 12. The arms 4 are provided with finger holds 14 for convenience in throwing the attachment up and down. 35 In view of the fact that the brackets 7 take the place of the ordinary top bearing plates of the platen shaft, one of which said plates carries the lock arm of the invariable line spacer, I provide the base 8 of one of my brackets with a spring lock arm 15, Fig. 45 which coats with the usual groove 16 of the platen shaft to control the line spacing in the usual manner.

In the endeavor to simplify my invention 50 by providing at attachment for the purpose which requires little or no changes in the machine, to apply it, and which is in itself a device wholly apart and separate from the machine, I have provided that my manifold- 55 ing ribbon shall be a short single-length section of approximately the length of the platen and detachably secured to and stretching under tension between the arms. 60 While it is true such a section is subject 65 to more rapid wear than a ribbon relatively

long and traveling between reels, it has controlling compensations, in that it avoids complexity, avoids such an intimate connection with the machine as to involve radical changes in its application, is cheap, and can be furnished in numbers to be used as required. Consequently an essential feature of my attachment is a manifolding ribbon comprising a single-length section approximately the length of the platen and carried by and between arms adapted to be turned to carry the ribbon into position to be placed between the sheets and into functional manifolding position. 70

Furthermore, it is essential that said ribbon section shall have means for readily attaching it to and detaching it from the carrying arms; and that these means be adapted for reversal of the ribbon edge for edge to prolong its life; and finally, that means be provided to hold the ribbon under tension. The ribbon fastening means may be of varied construction. A simple form is shown in Fig. 5, consisting of a clamp member 17 fitted to the ends of the ribbon, said member having a centrally disposed stud 17' which fits in a slot 18 in the ends of the arms 4. 80

Various means for maintaining tension on the ribbon may be employed. A simple way is to make the arms slightly resilient laterally and properly proportion the length of the ribbon. Then by pressing the arms towards each other the ribbon may be connected with them and then held under tension when the arms are released. 95

The ribbon 6 may be as shown in Fig. 5 one having an impression or ink surface 6' on one side only the other surface 6" being a non-impression one, or if thought best, in order to make one ribbon produce two carbons, one of which is a tissue paper sheet to be read by transmitted light, the ribbon may have both sides inked. 100

19 is a second rod extending between the arms 4, and carrying the usual form of paper presser rolls 20, Figs. 1, 3 and 4, adjustably and slidably mounted, as indicated in Fig. 1. 110

The use of my attachment is as follows: 115

Two loose sheets of paper are placed together in the machine, and rolled around the platen until their entered edges rise well above the index pointer B on the face of the platen. Then these edges are separated by the operator with one hand while with the other he drops the arms 4 down so that the manifolding ribbon 6 enters between said sheets. In moving to position the ribbon travels the eccentric or distorted path heretofore explained, by which it avoids the index pointer B which is pressing against the outer sheet, and then comes to rest clear of the platen surface. In this clear position, no interference is presented 120 125 130

to the free rolling of the sheets, so that said sheets can be moved as desired, with no danger of getting out of true relatively to each other. In fact by having no slippery sheet of carbon paper between them, said sheets, by skin friction, tend to remain firmly together. When the sheets are to be removed from the machine, they are simply rolled out by the platen or drawn out by hand 10 in the usual manner.

The attachment, it will be seen, is held firmly in both the elevated and depressed positions of the arms and ribbon by coacting impinging surfaces of the cams 11 and roll-

ers 12.

I claim:

1. A manifolding attachment for type-writing machines and the like, comprising a single-length section of manifolding ribbon; laterally resilient, spaced arms on the platen-carriage of the machine; a detachable connection between the ends of the manifolding section and said arms adapted to extend said section under tension between the arms, parallel with the platen; and a connection between said arms and the platen-carriage, adapting them to elevate said manifolding section above the platen in position to be entered between the sheets and to depress it therebetween to position in the line of type-impact.

2. An attachment for the described purpose comprising a rod mounted for axial movement on the machine frame, back of and parallel with the machine platen and above the horizontal plane of the axis of said platen; a pair of arms carried by said rod and spaced apart by a distance approximately equal to the platen length; a manifolding ribbon carried by and between the free ends of said arms in position when the arms are raised with the rod for an axis, to be entered between the sheets rolled up by the platen and when the arms are depressed, to be moved down between said sheets to the front of the platen in the line of type-impact; and means called into play by the rocking of the rod for automatically shifting said rod away from and toward the platen to distort the path of the ribbon for the purpose described.

3. An attachment for the described purpose comprising a rod mounted for axial movement on the machine frame back of and parallel with the machine platen and above the horizontal plane of the axis of said platen; a pair of arms carried by said rod and spaced apart by a distance approximately equal to the platen length; a manifolding ribbon carried by and between the

free ends of said arms, in position when the arms are raised with the rod for an axis, to be entered between the sheets rolled up by the platen and when the arms are depressed, to be moved down between said sheets to the front of the platen in the line of type-impact; and means called into play by the rocking of the rod for automatically shifting said rod away from and toward the platen to distort the path of the ribbon 70 for the purpose described, consisting of 65 slideable bearings for the rod, springs for controlling said bearings, and cams for sliding them.

4. A manifolding attachment for type-writing machines and the like comprising a rod; brackets in which the rod ends are journaled, said brackets having bases adapted for attachment to the platen carriage and forming top bearings for the platen 80 shaft; a pair of spaced arms carried by the rod; and a manifolding ribbon carried by and between the free ends of the arms in position when the arms are raised with the rod for an axis, to be entered between 85 the sheets rolled up by the platen, and when the arms are depressed, to be moved down between said sheets to the front of the platen in the line of type-impact.

5. A manifolding attachment for type-writing machines and the like comprising a rod; brackets in which the rod ends are journaled, said brackets being adapted for attachment to the machine frame in position to serve as top bearings for the platen 95 shaft and to carry the rod back of and parallel with said platen; a pair of spaced arms carried by the rod; a manifolding ribbon carried by and between the free ends of the arms in position when the arms are 100 raised with the rod for an axis, to be entered between the sheets rolled up by the platen, and when the arms are depressed, to be moved down between said sheets to the front of the platen in the line of type-impact; and means called into play by the 105 rocking of the rod for automatically shifting said rod away from and towards the platen, to distort the path of the ribbon, consisting of slideable bearings for the rod 110 in the brackets, springs for controlling said bearings and cams for sliding them.

In testimony whereof I have signed my name to this specification in the presence of two subscribing witnesses.
